TYPOGRAPHICAL COMPOSING MACHINE

Frank C. Frolander, Elizabeth, N. J., assignor to
Mergenthaler Linotype Company, a corpora-
tion of New York

Application January 22, 1938, Serial No. 186,352

20 Claims. (Cl. 199—16)

This invention relates to typographical composing machines, such as "Linotype" machines of the general organization represented in Letters Patent of the United States to O. Mergenthaler No. 436,532, wherein circulating matrices are released from a magazine in the order in which their characters are to appear in print and then composed into a line, the composed line transferred to the face of a slotted mold, the mold filled with molten metal to form a slug or Linotype against the matrices which produce the type characters thereon, and the matrices thereafter returned through distributing mechanism to the magazine from which they started.

More particularly, it relates to that class of machines designed to handle matrix fonts which differ from one another in the size and number of characters. These fonts, for example, may be the ordinary 90 character fonts used exclusively for the composition of "straight" matter and the special 72 character fonts used for the composition of head letter or display matter.

The machines of the particular class stated are adapted to employ a plurality of superposed magazines arranged in a shift frame movable to bring any one of the magazines into operative relation with a magazine entrance channel at the rear, through which the matrices enter the magazine from the distributing mechanism, and an assembler throat at the front through which the released matrices leave the magazine during the composition of a line.

Since 72 character and 90 character fonts may be used interchangeably in such machines, provision is made for adjusting the distributing mechanism and the assembling mechanism to correspond with the font in use at any time. The assembling mechanism includes two trains of connections, as for instance, two sets of reeds, either one of which can be selectively associated with the keyboard, one set for operating the escapement mechanisms associated with the magazines containing the 90 character fonts, and the other for operating the escapement mechanisms associated with the magazines containing the 72 character fonts, depending upon which type of font is in operative position.

Depending upon the class of work for which the machine is employed, it has been found desirable to provide for varying the arrangement or grouping in the shift frame, of the magazines containing the different fonts, i. e., a machine at one time may have one special 72 character font and the rest 90 character fonts, and at another time, two special 72 character fonts and the rest

90 character fonts, etc., and with the fonts arranged in different relative positions with respect to one another. In other words, a machine at different times may have magazine groupings varying both as to the number of 72 and 90 character fonts employed, as well as to the relative positions of the fonts in the shift frame.

To facilitate the use of such various magazine groupings, there is provided, in accordance with the present improvements, mechanism which is adjustable in accordance with the grouping of the magazines, and which operates automatically to select the appropriate train of connections or set of reeds for use with the operative font. In the embodiment of the invention illustrated, the improved mechanism includes a cam device, the peripheral configuration of which determines the selection of the appropriate set of reeds, and which is manually adjustable to bring different portions of its periphery into use, depending upon the specific font grouping.

Referring to the drawings:

Fig. 1 is a side elevation of a portion of a Linotype machine equipped with the present improvements;

Fig. 2 is a plan view, partly in section, of the cam device for operating the reed selecting mechanism;

Fig. 3 is a rear elevation of the parts shown in Fig. 2; and

Figs. 4 to 7 are face views of the cam device, showing the different positions it will occupy for one specific grouping of fonts.

The machine shown in the drawings (see Fig. 1) is equipped with four superposed magazines A¹, A², A³, A⁴, the lower two, A³, A⁴ being of standard form, that is provided with 91 grooves or channels spaced apart in the usual way to adapt them to contain a regular 90 character font, whereas the upper two, A¹, A², although of the same width as the magazines A³, A⁴, are provided each with only 73 grooves or channels spaced apart in a different manner to adapt them to contain a 72 character display font.

The magazines A¹, A², A³, A⁴ are mounted on separate base frames A⁵ connected together at the rear by upright side plates A⁶, and constituting a shift frame A⁷, which is arranged to be raised and lowered in the well known manner by operation of a hand crank R, so as to bring any selected one of the magazines into operative position.

When either of the two lower magazines A³, A⁴ is in operative position, the regular magazine entrance B is employed to deliver the matrices

thereto from the distributing mechanism and, when either of the two upper magazines A¹, A² occupies such operative position, the special magazine entrance C is so employed. The two entrances differ in the number and spacing of their partition plates, the entrance B presenting 91 channels to cooperate with the magazines A₃, A₄, and the entrance C presenting but 73 channels to cooperate with the magazines A¹, A². The entrances B and C, arranged in inverted relation to each other, are rotatably mounted so that either may be brought into the operative position, as desired. Their individual supporting frames are fastened together and constitute a reversible holder or support, which is arranged so that it may be given successive half turns to bring first one entrance and then the other into use.

The machine is equipped with a distributor comprising two distinct distributor bars B¹, C¹ and a common set of matrix conveying screws H. The bar B¹ is provided with 91 toothed combinations equally spaced apart to correspond to the spacing of the matrix channels in the magazine entrance B and the regular magazines A³, A⁴; whereas, the bar C¹ is provided with only 73 combinations which are unequally spaced apart to correspond to the spacing of the matrix channels in the magazine entrance C and the special magazines A¹, A². The distributor bars B¹ and C¹ are pivotally mounted, so that either may be rocked into operative relation to the conveying screws H, depending upon whether the entrance channel B or the entrance channel C is in operative position.

As the matrices are released from the individual magazines for composition in line, they enter the assembler entrance V which presents a vertical main section V¹ and a pair of throat sections V², V³. The main section V¹ is made up of a back plate V⁴, a cover plate V⁵ and a series of intervening partitions V⁶, the said back and partitions being cut away at the top to accommodate the throat sections V², V³. These throat sections are inverted with relation to each other and are rotatably mounted for interchange, one of the throat sections being employed when a 72 character font is in operative position, and the other when a 90 character font is in operative position. An ordinary hinged transparent plate V⁷ is employed to deflect the matrices downwardly as they pass through the individual throat sections V² or V³, this plate being common to both throat sections and serving as the upper wall of each selected section.

The magazines A¹, A², A³, A⁴ are each provided with escapements a, which control the release of the matrices therefrom and which are adapted to be actuated when the selected magazine is in operative position by a series of pivoted levers P. The levers are alined horizontally and operated from a keyboard P¹ through connections which may include two series of vertically disposed reeds P², P³, arranged one behind the other and having their lower ends terminating above the keyboard P¹.

The reeds P² (91 in number) of the front set are substantially straight and have their upper ends arranged to engage all the escapement actuating levers P; whereas the reeds P³ (73 in number) of the rear set, while having their lower end portions alined with corresponding reeds of the front set, are offset in different directions and to different extents to locate their upper end portions in engaging relation to selected levers P¹.

which cooperate with the escapements associated with the 72 font magazines. The reeds P², P³ are operated by a series of fore-and-aft levers P⁴ controlled from the finger keys of the keyboard through the usual series of power-operated cam yokes (not shown) and a single series of short reed sections or rods P⁵.

The levers P⁴ are pivotally mounted and guided at their rear ends in an adjustable bar P⁶ and formed near their front ends with upward projections p. The bar P⁶ is mounted in a fixed horizontal supporting frame P⁷ and is slidable forwardly and backwardly therein to locate the projections p of the levers P⁴ in operative relation to the front and rear sets of reeds P², P³, respectively.

So far as described, the parts, their construction and mode of operation are or may be the same as disclosed in the Burt Patent No. 1,928,716, and to which reference may be had, if desired.

According to the present improvements, the bar P⁶ is moved to its different positions of adjustment through the medium of a horizontal rock shaft E journalled in the supporting frame P⁷ and a pair of depending arms E¹ pinned at the opposite ends of said rock shaft and which, at the bottom, are connected, through links E², to depending portions of the bar P⁶, the arrangement being such that, as the shaft E is rocked in a counterclockwise direction, looking at the machine from the right, the bar P⁶ moves to its rearmost position, wherein the levers P⁴ are in position for actuating the reeds P³ (those for operating the escapements of the 72 character fonts); whereas, when the shaft is rocked in the opposite direction, the bar P⁶ is moved forwardly to locate the levers P⁴ in position to operate the reeds P² (those for operating the escapements of the 90 character fonts).

The operation of the rock shaft E is controlled from a pair of cams F, F¹ through a double-armed lever E³ pinned to the shaft and provided at its ends with anti-friction rollers E⁴, E⁵, the roller E⁴ being arranged to track along the periphery of the cam F, whereas the other roller E⁵ is arranged to track along the periphery of the cam F¹. The cams F, F¹ are complementary in their peripheral edges, i. e., when a high portion of the cam F is opposite its associated anti-friction roller E⁴, a low portion of the cam F¹ is opposite its associated anti-friction roller E⁵, and for this position of the parts the levers P⁴ will occupy their rearmost positions of adjustment; and conversely, when a low portion of the cam F is opposite the anti-friction roller E⁴, a high portion of the cam F¹ is opposite the anti-friction roller E⁵, so as to cause the levers P⁴ to occupy their forward positions of adjustment. In other words, the cam arrangement is such that the rock shaft will be moved to its different positions positively by the arrival of a high portion of one or another of the cams opposite its respective roller, accompanied by the simultaneous arrival of a low portion of the other cam opposite its respective roller.

As shown in Fig. 2, the cams are screwed together, thus operating as a unit which is splined to a sleeve G rotatably mounted on a shaft G¹ supported at one end in a portion of the fixed bracket P⁷. The sleeve is also supported during its rotation in a bearing P⁸ presented by another portion of the bracket P⁷ and through which the sleeve extends. Endwise movement of the cams with respect to the sleeve is prevented by a small set screw f threaded into a hole drilled in the hub 75

portion of one of the cams and which engages in a recess formed in the sleeve G.

The rotation of the cams F, F¹ to effect the rocking of the shaft E is controlled by the vertical movement of the shift frame through the medium of a long vertical link J (see Fig. 1) pivoted at its upper end to a lug projecting from the lowermost member of the frame A⁷. At its lower end, the link is formed with an elongated slot J¹, which engages a cross pin J² mounted at the rear end of a crank arm F² journaled at its front end on the shaft G¹, and which has a hub portion in the form of a plate F³ connected in a manner, hereinafter described, to the cam unit. According to this arrangement, as the shift frame is moved upwardly, the cam unit, through the connections just described, will be rotated in a counterclockwise direction; whereas, when the shift frame is moved downwardly, the cam unit will be rotated in the reverse direction.

Under normal operating conditions, the crank arm F² is connected to its operating link J at a definite point near the center of the slot J¹. However, as a safety precaution, this connection has been designed to permit the link to move with respect to the cross pin J², in the event some obstruction is presented to the movement of the cam unit. As shown in Fig. 3, the connection includes a circular member J³ having a pair of guiding lugs J⁴ extending into the slot J¹ in the link and a pair of projections J⁵ having bevelled surfaces engaging in notches formed in the link to receive them. The link J and crank arm F² are held together between a head J⁶ with which the cross pin J⁷ is provided and the member J³ by a spring J⁷ reacting between the member and a washer J⁸ held in place by a pair of lock nuts J⁹ threaded onto the end of the cross pin. The force of the compression spring is sufficient, under ordinary circumstances, to maintain the proper connection between the link and the crank arm. Should some obstruction be presented to the movement of the parts, the bevelled projections J⁵ on the member J³ will be cammed out of the notches in the link J, so that the latter can move with respect to the cross pin, with no consequent damage to the parts.

Since the complete travel of the shift frame from a position, wherein the topmost magazine A¹ is in operative position to a position wherein the lowermost magazine A⁴ is in operative position and back again, involves only a partial rotation of the cam unit, it is apparent that, if the portions of the cam peripheries which cooperate with the rollers E⁴, E⁵ are formed with high portions and low portions in a given relation or sequence, depending upon the grouping of fonts in the shift frame, the rotation of the cams in accordance with the movement of the shift frame can be made to operate the bar P⁶ in a manner to locate the levers P⁴ in operative relation with the series of reeds P³ when a magazine containing a 72 character font is in operative position, and in operative relation with the series of reeds P² when a magazine containing a 90 character font is in operative position. Thus, in the illustrative embodiment, the magazine grouping is one wherein the two upper magazines contain special 72 character fonts, and the two lowermost magazines regular 90 character fonts. The setting of the cams F, F¹ for this magazine grouping is illustrated in Figs. 4 to 7. In accordance with this setting, when the topmost magazine is in operative position, the cams F, F¹ and the rock shaft E operated thereby will have the relative positions shown in Fig. 4 and, under these conditions, the bar P⁶ will occupy

its rearmost position, wherein the levers P⁴ are in operative association with the reeds P³. In the relative positions shown, a high portion of the cam F is located opposite the roller E⁴; whereas a low portion of the cam F¹ is located opposite the roller E⁵.

If the shift frame is now raised to bring the second 72 character font into operative position, the cam unit is turned to the position shown in Fig. 5, wherein, it will be observed, there is still a high portion of the cam F opposite its roller E⁴ and a low portion of the cam F¹ opposite the roller E⁵. Consequently, the shaft E will not be rocked, so that the relative positions of the levers P⁴ and the reeds P³ will be as before. Now, if the shift frame is raised to bring the third magazine into operative position, which, as will be recalled, contains a 90 character font, the cam unit will be rotated to the position shown in Fig. 6. During this rotation of the cam unit and by virtue of its configuration, a low portion of the cam F will arrive opposite the roller E⁴, and a high portion of the cam F¹ opposite the roller E⁵, thus causing the rock shaft E to be turned in a clockwise direction to the position shown and, as it is thus turned, the bar P⁶ will be moved to its foremost position of adjustment to locate the levers P⁴ in operative association with the reeds P², i. e., those for operating the escapements associated with a 90 character font. And similarly, if the shift frame is again raised to bring the lowermost magazine, which likewise contains a 90 character font, into operative position, the cam unit will be turned to the position shown in Fig. 7, wherein another low portion of the cam F is opposite the roller E⁴ and a high portion of the cam F¹ opposite the roller E⁵. As this movement of the cam involves no movement of the rock shaft, the previous adjustment of the levers P⁴, wherein they are operatively associated with the reeds P² for operating the escapements of a 90 character font will be maintained. And regardless of whether the shift frame is moved up or down, the arrival of any magazine in operative position will automatically locate the cam unit in a position, wherein the levers P⁴ will be positioned for operating the set of reeds corresponding to the font in that particular magazine.

From what has been said, it will be apparent that, for any grouping of 72 and 90 character fonts in the shift frame, the levers P⁴ can be shifted to render the appropriate set of reeds P², P³ active by rotatively adjusting the cam unit to different positions and designing the cams thereof with high and low portions following one another in such order that, as the shift frame is moved throughout its full range of travel, the active portion of the cam unit will cause the rock shaft to be turned to adjust the levers P⁴ into a position to cooperate with the rear set of reeds P³ when a 72 character font is moved into operative position, and into a position to cooperate with the front set of reeds P² when a 90 character font is moved into operative position. In the illustrative embodiment of the invention, the cam unit is adjustable to twelve different positions with respect to the crank arm F² and, for each different adjustment, the configuration of the active portion of its peripheral edges corresponds to a different grouping of fonts in the shift frame.

Referring to Figs. 2 to 7, it will be noted that the cam unit is formed with twelve holes F⁴ equally spaced along a circular pitch line near the outer edge of the cam F, three of which in any given setting of the unit, will be engaged

by three studs F⁵ projecting laterally from the face of the plate F³ forming part of the hub of the crank arm F². The operative engagement of the cam unit with the studs, and consequently 5 with the crank arm, is maintained by a compression spring G² encircling a reduced portion of the sleeve G on which the cam unit is mounted and located within the confines of the bearing P⁸. The spring reacts between an annular shoulder 10 G³ presented by the sleeve and a circular plate G⁴ through which the sleeve extends and which is fastened at one end of the bearing P⁸, as by screws g. A cylindrical dial G⁵, formed with a knurled portion, is fixedly mounted at the end 15 of the sleeve G to facilitate the adjustment of the cam unit.

According to this arrangement, the proper adjustment of the cam unit for any given grouping of fonts in the shift frame is obtained by pulling 20 the dial against the action of the spring G² from the solid line position shown in Fig. 3 to the dotted line position shown therein, or until the cam unit clears the studs F⁵, thence turning the dial to the setting required by the font 25 grouping, and thereafter releasing it, thus allowing the cam unit to be restored to its normal position, under the action of the spring G², the studs F⁵ at this time entering a different set of holes F⁴ in the cam unit and which correspond 30 to the new setting.

The proper setting of the cam unit for a given grouping of fonts in the shift frame is indicated by different legends G⁶ arranged around the cylindrical surface of the dial, in 35 cooperation with a pointer P⁹ formed in the outer surface of the bearing P⁸. The legends represent different magazine groupings and, when any one thereof registers with the pointer, the cam unit will be located in a position properly to adjust the levers P⁴ to select the proper 40 set of reeds P², P³ for operation with the different fonts of a group in the shift frame and which corresponds to such legend. Thus, as previously stated, the illustrative embodiment 45 depicts a grouping, wherein the upper two magazines contain 72 character fonts and the lower two magazines 90 character fonts. The adjustment of the cam unit for this grouping is illustrated in Fig. 3, wherein it will be observed that the legend in register with the pointer bears the 50 notation "72—72 90—90". If the upper three magazines in the shift frame contained each a 72 character font and the lowermost magazine a 90 character font, the proper setting of the cam unit for such grouping would be obtained 55 by adjusting the dial in a clockwise direction through one space, looking at the parts from the left in Fig. 3 or if the uppermost and lowermost magazines in the shift frame contained each a 72 character font and the two intermediate magazines, each a 90 character font, the proper setting of the cam unit for such grouping would be obtained by adjusting the dial in the opposite direction through one space from 60 the position shown in Fig. 3, the adjustments referred to being indicated by the legends on the dial. And in the same manner, the cam unit can be adjusted for any grouping of fonts in the shift frame, merely by adjusting the dial 65 to the proper setting, as indicated by the various legends thereon.

At this point, it might be stated that, while each adjustment of the cam unit renders four positions thereof active for a group of four fonts, 70 the sequence of high and low portions is such

that it is necessary only to adjust it through one position to enable its use for a different grouping of four fonts. In this way, the size of the various parts is materially diminished.

In the embodiment illustrated, the improved mechanism has been designed to accommodate twelve different font groupings, and this number will be sufficient for ordinary commercial use. However, it will be apparent that the mechanism could be employed for a larger number of font groupings, if desired, merely by changing the peripheral configuration of the cams and the number of legends on the dial in accordance with the teachings herein disclosed. Furthermore, it will be understood that 15 the present improvements are not limited to a four magazine machine, but are applicable equally as well to a machine adapted to employ a larger or a smaller number of magazines.

In the accompanying drawings, the invention 20 has been shown merely by way of example and in preferred form, and obviously many variations and modifications may be made therein which will still be comprised within its spirit. It is to be understood, therefore, that the invention 25 is not limited to any specific form or embodiment, except insofar as such limitations are specified in the appended claims.

Having thus described my invention, what I 30 claim is:

1. A typographical composing machine adapted to be equipped with a plurality of differently channelled magazines capable of being grouped in various relative positions and including, in combination, means for rendering any selected magazine operative for the release of matrices therefrom, key-controlled mechanism for releasing the matrices from the magazines for composition and including two trains of connections selectively operable according to the channeling in the magazines, and means adjustable in accordance with the grouping of the magazines for automatically selecting the appropriate train of connections for use with the operative magazine.

2. A typographical composing machine according to claim 1, wherein the means for automatically selecting the appropriate train of connections is actuated as the respective magazines are rendered operative for the release of matrices therefrom.

3. A typographical composing machine adapted to be equipped with a plurality of differently channelled magazines capable of being grouped in various relative positions and including, in combination, means for rendering any selected magazine operative for the release of matrices therefrom, key-controlled mechanism for releasing the matrices from the magazines for composition and including two trains of connections selectively operable according to the channeling in the magazines, and means including a cam device adjustable in accordance with the grouping of the magazines for automatically selecting the appropriate train of connections for use with the operative magazine.

4. A typographical composing machine adapted to be equipped with a plurality of differently channelled magazines capable of being grouped in various relative positions and including, in combination, means for rendering any selected magazine operative for the release of matrices therefrom, key-controlled mechanism for releasing the matrices from the magazines for composition and including two trains of connections selectively operable according to the channeling in the mag-

azines, and means including a cam device adjustable to a plurality of different settings and adapted in each setting and upon operation to select the appropriate train of connections for use with the respective magazines of a different magazine grouping.

5. A typographical composing machine adapted to be equipped with a plurality of differently channeled magazines capable of being grouped in various relative positions and including, in combination, means for moving the magazines to bring any one thereof into operative position for the release of matrices therefrom, key-controlled mechanism for releasing the matrices from the magazines for composition and including two trains of connections selectively operable according to the channeling in the magazines, and means adjustable in accordance with the grouping of the magazines for automatically selecting the appropriate train of connections for use as a given magazine is moved into operative position.

6. A typographical composing machine adapted to be equipped with a plurality of differently channeled magazines capable of being grouped in various relative positions and including, in combination, means for rendering any selected magazine operative for the release of matrices therefrom, key-controlled mechanism for releasing the matrices from the magazines for composition and including two sets of reeds selectively operable according to the channeling in the magazines, and means adjustable in accordance with the grouping of the magazines for automatically selecting the appropriate set of reeds for use with the operative magazine.

7. A typographical composing machine according to claim 6, wherein the means for automatically selecting the appropriate set of reeds is actuated as the respective magazines are rendered operative for the release of matrices therefrom.

8. A typographical composing machine adapted to be equipped with a plurality of differently channeled magazines capable of being grouped in various relative positions and including, in combination, means for rendering any selected magazine operative for the release of matrices therefrom, key-controlled mechanism for releasing the matrices from the magazines for composition and including two sets of reeds selectively operable according to the channeling in the magazines, and means including a cam device adjustable in accordance with the grouping of the magazines for automatically selecting the appropriate set of reeds for use with the operative magazine.

9. A typographical composing machine adapted to be equipped with a plurality of differently channeled magazines capable of being grouped in various relative positions and including, in combination, means for rendering any selected magazine operative for the release of matrices therefrom, key-controlled mechanism for releasing the matrices from the magazines for composition and including two sets of reeds selectively operable according to the channeling in the magazines, and means including a cam device adjustable to a plurality of different settings and adapted in each setting and upon operation to select the appropriate set of reeds for use with the respective magazines of a different magazine grouping.

10. A typographical composing machine adapted to be equipped with a plurality of differently channeled magazines capable of being grouped in various relative positions and including, in

combination, means for moving the magazines to bring any one thereof into operative position for the release of matrices therefrom, key-controlled mechanism for releasing the matrices from the magazines for composition and including two sets of reeds selectively operable according to the channeling in the magazines, and means adjustable in accordance with the grouping of the magazines for automatically selecting the appropriate set of reeds for use as a given magazine is moved into operative position.

11. A typographical composing machine adapted to be equipped with a plurality of differently channeled magazines capable of being grouped in various relative positions and including, in combination, a shift frame wherein the magazines are mounted and movable to bring any selected one of the magazines into operative position for the release of matrices therefrom, key-controlled mechanism for releasing the matrices from the magazines for composition and including two trains of connections selectively operable according to the channeling in the magazines, and means adjustable in accordance with the grouping of the magazines and operated by the movement of the shift frame automatically to select the appropriate train of connections for use with the selected magazine.

12. A typographical composing machine adapted to be equipped with a plurality of differently channeled magazines capable of being grouped in various relative positions and including, in combination, a shift frame wherein the magazines are mounted and movable to bring any selected one of the magazines into operative position for the release of matrices therefrom, key-controlled mechanism for releasing the matrices from the magazines for composition and including two trains of connections selectively operable according to the channeling in the magazines, means including an adjustable cam device operated by the movement of the shift frame automatically to select the appropriate train of connections for use with the respective magazines of a given grouping, and means for adjusting the cam device for other magazine groupings.

13. A typographical composing machine adapted to be equipped with a plurality of differently channeled magazines capable of being grouped in various relative positions and including, in combination, means for rendering any selected magazine operative for the release of matrices therefrom, key-controlled mechanism for releasing the matrices from the magazines for composition and including two trains of connections selectively operable according to the channeling in the magazines, means including a cam device adjustable to a plurality of different settings and adapted in each setting and upon operation to select the appropriate train of connections for use with the respective magazines of a different magazine grouping, and means for adjusting the cam device including an element bearing legends indicative of the various magazine groupings.

14. A typographical composing machine adapted to be equipped with a plurality of differently channeled magazines capable of being grouped in various relative positions and including, in combination, a shift frame wherein the magazines are mounted and movable to bring any selected one of the magazines into operative position for the release of matrices therefrom, key-controlled mechanism for releasing the matrices from the magazines for composition and including two trains of connections selectively operable accord-

- ing to the channeling in the magazines, means including an adjustable cam device operated by the movement of the shift frame automatically to select the appropriate train of connections for 5 use with the respective magazines of a given grouping, and means for adjusting the cam device for other magazine groupings, said means including a dial bearing legends indicative of the various magazine groupings for which the cam 10 device can be adjusted.
15. A typographical composing machine adapted to be equipped with a plurality of differently channelled magazines capable of being grouped in various relative positions and including, in combination, means for rendering any selected magazine operative for the release of matrices therefrom, key-controlled mechanism for releasing the matrices from the magazines for composition and including two trains of connections selectively operable according to the channeling in the magazines, and means including a cam device adjustable to a plurality of different settings to render different portions of the cam device active and adapted in each setting and upon operation 20 to select the appropriate train of connections for use with the respective magazines of a different magazine grouping, the active portions of the cam device in the different settings overlapping one another.
- 25 16. A typographical composing machine adapted to be equipped with a plurality of differently channelled magazines capable of being grouped in various relative positions and including, in combination, means for rendering any selected magazine operative for the release of matrices therefrom, key-controlled mechanism for releasing the matrices from the magazines for composition and including two trains of connections selectively operable according to the channeling 30 in the magazines, and means including a cam device rotatably adjustable to a plurality of different settings and adapted in each setting and upon operation to select the appropriate train of connections for use with the respective magazines 35 of a different magazine grouping, and means for manually rotating the cam device to effect the desired adjustment.
- 40 17. A typographical composing machine adapted to be equipped with a plurality of differently channelled magazines capable of being grouped in various relative positions and including, in combination, a shift frame wherein the magazines are mounted and movable to bring any selected one of the magazines into operative position for 45 the release of matrices therefrom, key-controlled mechanism for releasing the matrices from the magazines for composition and including two trains of connections selectively operable according to the channeling in the magazines, and 50 means adjustable in accordance with the grouping of the magazines and operated positively by the shift frame as it is moved to bring a selected magazine into operative position automatically to select the appropriate train of connections for use with the selected magazine.
- 55 18. A typographical composing machine adapted to be equipped with a plurality of differently channelled magazines capable of being grouped in various relative positions and including, in combination, a shift frame wherein the magazines are mounted and movable to bring any selected one of the magazines into operative position for the release of matrices therefrom, key-controlled mechanism for releasing the matrices from the magazines for composition and including two trains of connections selectively operable according to the channeling in the magazines, and means including a cam for each train of connections adjustable in accordance with the grouping of the magazines and operated positively by the shift frame as it is moved to bring a selected magazine into operative position automatically to select the appropriate train of connections for use with the selected magazine.
- 60 19. A typographical composing machine adapted to be equipped with a plurality of differently channelled magazines capable of being grouped in various relative positions and including, in combination, a shift frame wherein the magazines are mounted and movable to bring any selected one of the magazines into operative position for the release of matrices therefrom, key-controlled mechanism for releasing the matrices from the magazines for composition and including two trains of connections selectively operable according to the channeling in the magazines, means adjustable in accordance with the grouping of the magazines and operated positively by the shift frame as it is moved to bring a selected magazine into operative position automatically to select the appropriate train of connections for use with the selected magazine, and safety mechanism intermediate the shift frame and said means for preventing damage to the parts in the event of an obstruction to the operation thereof.
- 65 20. A typographical composing machine adapted to be equipped with a plurality of differently channelled magazines capable of being grouped in various relative positions and including, in combination, a shift frame wherein the magazines are mounted and movable to bring any selected one of the magazines into operative position for the release of matrices therefrom, key-controlled mechanism for releasing the matrices from the magazines for composition and including two trains of connections selectively operable according to the channeling in the magazines, means including a cam for each train of connections adjustable in accordance with the grouping of the magazines and operated positively by the shift frame as it is moved to bring a selected magazine into operative position automatically to select the appropriate train of connections for use with the selected magazine, and a yielding connection intermediate the shift frame and the cams for preventing damage to the parts in the event of an obstruction to the operation thereof.
